UNITED STATES PATENT OFFICE.

FRANK H. QUADE, JR., OF FRESNO, CALIFORNIA.

PRINTING-MACHINE.

1,195,853.

Specification of Letters Patent. Patented Aug. 22, 1916.

Application filed August 2, 1913. Serial No. 782,729.

To all whom it may concern:

Be it known that I, FRANK H. QUADE, Jr., a citizen of the United States, and a resident of the city of Fresno, county of Fresno, 5 and State of California, have invented new and useful Improvements in Printing-Machines, of which the following is a specification.

My invention relates to printing machines 10 and the particular object thereof is to improve the machine shown in the United States Letters Patent issued to John F. Mahlstedt, numbered 1,016,756, Feb. 6, 1912; 1,018,434, Feb. 27, 1912; 1,041,814, Oct. 15, 15 1912.

The machine shown in said patents is for the purpose of printing letters, circulars, and so forth, in which the heading of the letter may be printed with ordinary printing ink of any desired color, the body of the letter with an inked ribbon to imitate typewriting, and the signature with ink which will give the effect of hand writing.

The object of this invention is to improve 25 and simplify such printing machine, and make it more certain and efficient and less liable to get out of order, the present invention relating especially to the means for feeding the paper to and past the impression roller 30 or printing means, and it consists in certain novel features hereinafter first fully described and then particularly pointed out in the claims following the description.

Referring to the drawings: Figure 1 is 35 a side view of the machine complete; Fig. 2 is a longitudinal section of the machine through the center, showing a portion of the mechanism; Fig. 3 is a perspective view of the paper feed mechanism; Fig. 4 is a perspective view of the eccentric bushing for adjusting the lower feed roll; Fig. 5 is an end view of combination bail post and pacifier; Fig. 6 is a sectional view of paper feed and ejector mechanism showing platen and 45 feed rolls up and paper stops down ready to receive paper before printing; Fig. 7 is a similar view showing platen and feed rolls down and paper stops up ready for printing; Fig. 8 is a plan view of the means for 50 ejecting printed paper; Fig. 8^a is an elevation of an auxiliary ejector; Fig. 9 is a plan view of the paper guide between feed rolls and means for supporting same; Fig. 10 is end view of left hand journal box and 55 feed plate; Fig. 11 is end view of right hand

journal box and feed plate; Fig. 12 shows in detail the support for the paper guide; Fig. 13 is a top view of bail shaft and upper feed roll mounted with idle gear and driving gear, showing part cut away, and bearing pins; Fig. 14 is an elevation of the locking mechanism for raising and lowering the platen; Fig. 15 is top view of paper feed table; Fig. 16 is a sectional view of paper feed table taken on line a—a, Fig. 15; Fig. 17 is an elevation showing the manner of supporting and locking the feed table in its operative position; Fig. 18 is a perspective view of the bracket on the feed table; Fig. 19 is a detail view of the parts coöoperating 70 with the bumper block disassembled and in perspective; Fig. 20 is a detail of the bumper block and the trip which is mounted thereon.

The supporting frame is provided at each 75 end with a pair of legs 212 and 213 connected by a brace 214 which serves as a support for a motor 210 and the bearing or fulcrum 221 for the oscillatory lever 215. A circuit closer 239 for controlling the motor is also 80 mounted on one of the legs.

201 is the main shaft mounted in bearings 202, which shaft carries a fly wheel and a pinion 207. Pinion 207 engages with main drive gear 205 which is mounted on crank 85 shaft 204 working in bearings 203.

219 is a connecting link and is journaled on crank shaft 204 at one end and journaled at the other end to the approximate lineal center of vertical driving lever 215. The 90 lower end of vertical driving lever 215 is journaled in bearing 221 on brace 214, and the upper end of said lever is connected by a link 216 to the moving type bed 93 which slides longitudinally in a track formed in 95 the main frame 138.

79 is a lever which controls the printing and the ribbon feed as hereinafter described. It is pivoted to the side of the main frame 138 by pivot 79^a which acts as a fulcrum 100 for said lever. The hole in lever 79 through which pivot 79^a passes is elongated longitudinally.

79^b is a locking notch in lever 79 which engages with a bracket 242 on the main 105 frame when the lever is raised, and said lever is raised and held in such upward position by spring 81.

80 is a cushion handle on the upper extremity of lever 79. By downward pressure 110

- on cushion handle 80, lever 79 is disengaged from bracket 242, and the paper feed mechanism, ribbon mechanism, and printing mechanism are thrown out of operation.
- 6 69 is a rod which has intermittent longitudinal sliding movement on the top of the main frame 138 for raising and lowering the platen and for operating the paper feed mechanism. This rod is kept in position 10 by a pin 72 working in a slot in said rod 69 at one end and a screw or post 71 working in a slot in said rod at the other end.
- 10 92 is a post on rod 69 at a point between screw 71 and pin 72.
- 15 70 is a tension spring attached at one end to post 92 and at the other to post 71.
- 20 73 is a locking block attached to the rod 69 near the end thereof, the function of which will be hereinafter set forth. At the 25 ends of rod 69 are bumper straps 69^a and 69^b which I have preferred to construct in the form of downturned right angle extensions to the rod. These bumper straps slide on the inside of frame 138 and in line with the 30 track on which the type bed slides. The length of rod 69 is slightly shorter than the stroke of the type bed 93, and as the type bed approaches the end of its track, a bumper block 243 thereon comes in contact 35 with bumper-strap 69^b and gives it and the rod a short longitudinal motion. This bumper block is shown in Fig. 20 and indicated in Fig. 2. As type bed 93 approaches bumper-strap 69^a, it would normally move 40 rod 69 back the same direction the bed is traveling. I have, however, provided a lock latch 74 for locking operating rod 69, said latch 74 consisting of an angle lever or L-shaped dog having perpendicular and horizontal arms and pivoted near the angle or junction of the arms to a bracket (shown in Fig. 2) attached to frame 138. On the end of the horizontal arm of the latch is a catch 45 74^a which normally engages with locking block 73. I have pivoted one end of a rod 75 to lever 79 below the fulcrum thereof and the other end of this rod passes through a hole in the lower end of the latch 74 and is equipped at its extremity with an adjustable collar 78. Collar 78 is adjusted on rod 75 so that when lever 79 is perpendicular latch 74 can engage block 73, but when lever 79 is released from its vertical position, collar 78 engages with the lower end 55 of latch 74 and holds it disengaged from block 73 as indicated in dotted lines in Fig. 14.
- 60 76 is a spiral compression spring surrounding rod 75 between latch 74 and an adjustable collar 77 fitted on the rod between the latch and the lever 79. When the latch 74 is engaged with locking block 73, it is held in such position by spring 76. The catch has an inclined face 74^a, as shown 65 clearly in Figs. 14 and 19 and the bumper

block 243 on the type bed is constructed with a projection 243^a to slide under the catch as the type bed moves toward the forward end of the press, thus raising latch 74 at each stroke of the type-bed when the 70 lever 79 is in upright position.

3 is the platen or impression roller, the function of which is to press the paper on the type while printing. It is mounted on the right side in bearing block 1 and on the 75 left side in bearing block 2 which are attached rigidly to either side of frame 138. It receives motion from rack 160 mounted on moving type-bed 93 which engages with cog-wheel 4 attached to right hand end of 80 platen 3.

8 is an eccentric shaft which passes horizontally through center of the platen and carries, between the left hand end of the platen and the left hand journal box 2, a 85 pinion 5.

Pinion 5 engages a short adjustable rack 47 which is mounted on rod 69 between the rear end of the press and the lever 79. Said rack 47 is adjusted longitudinally by means 90 of a screw 64 and a thumb nut 65 thereon working between posts 67 attached to rod 69.

66 is a split spring washer between post 67 and thumb nut 65. This washer will lock thumb nut 65 in any position desired.

68 and 68^a are stop pins projecting from rod 69 beyond each end of rack 47. The adjustment of said rack 47 forward or backward is for the purpose of adjusting the pressure on the paper being printed.

The shaft 8 passing through the platen 3, as heretofore referred to, has an eccentric portion which rotates in a core 3^a inside of the platen. The pinion 5 meshes with the rack 47, and as rod 69 and the rack move backward in the intermittent motion hereinbefore described, shaft 8 turns in core 3^a and lowers the platen which will stay in the lowered position until the type-bed and rod 69 move to the forward end of the machine, whereupon said rack 47, moving with rod 69, will operate pinion 5 in a reverse direction from that previously given and thus raise the platen from the type. If lever 79 were released from its vertical position, 105 latch 74 would not lock rod 69 and, as spring 76 would hold rod 69 normally to the front of the machine, the platen would be lowered only at the rear end of the stroke, and be raised while the type-bed 110 passed under it.

Referring to Fig. 13, 15 is a bail shaft for supporting the upper paper feed roll. I prefer to make said shaft hexagonal, having attached thereto at the right hand end a bracket 16 and near the opposite end a similar bracket 16^a. Brackets 16 and 16^a support rod 19 for upper feed roll, said rod being locked in position by a pin 23 passing through the end of the rod and bracket 16^a.

17 is a shoulder bushing fitted and fastened on bail shaft 15 against bracket 16. Said bushing 17 provides a circular bearing for the intermediate gear 18 which meshes with 5 and receives its power from gear 4. 20 is a hollow tube having bushings 21 mounted in both ends thereof which bushings revolve on rod 19. For feeding the paper, I have mounted on hollow tube 20 a plurality of 10 short feed roll rubbers 22, the combination of which is herein termed the upper feed roll. On hollow tube 20, I have rigidly attached a gear 24 which meshes with the intermediate gear 18. Bail shaft 15 is mounted 15 in journal boxes 1 and 2 by means of bearing pins 25 and 25^a. On the left hand end of bail shaft 15 I have mounted the combination bail post 34 shown in Fig. 5 by passing said bail shaft through a hole in 20 the member 34^a of the post and designated 15^a on said figure. I have used clamp screw 36 to rigidly fasten the post to the bail shaft. Bail post 34 has a downward projection 34^b carrying a roller 35 and also has a horizontal arm 34^c through the end of which passes a pacifier lift screw 31 to be herein-after referred to. The upper feed rolls 22 receive pressure downward by means of 25 compression spring 37 which bears on the top of bail post 34 at a point between roller 35 and bail shaft 15. 38 is a guide pin inserted in the upper part of bail post 34 directly under spring 37, and 40 is an adjusting screw for regulating the downward pressure of upper feed roll. 39 is a guide washer carried on the lower end of screw 40 and riding on the top of compression spring 37. 42 is a bracket projecting from journal box 2 through which screw 40 passes. 40 41 is a lock nut for binding screw 40. The brackets 16 and 16^a extend from bail shaft 15 in the same general direction as arm 34^a of bail post 34, and it will be noted that by compressing spring 37 the downward pressure 45 on the upper feed roll is increased. 11 is the lower feed roll. It runs parallel to and directly upon the upper feed roll. It is journaled on the left in the left hand journal box 2 with a nonadjustable bearing and 50 on the right side in journal box 1 with an adjustable bearing, clearly shown in Fig. 4 in which 12 represents an eccentric bushing into which is inserted the right hand end of lower roll 11. 13 is a locking device which 55 is attached to the end of the eccentric bushing 12 and which, when the right hand bearing of lower roll 11 is adjusted in journal box 1, is on the outside of said journal box 1, as shown in Fig. 3. 13^a is a segmental slot in locking device 13. It will be observed 60 that by swinging the locking device 13 to the left or to the right the eccentric bushing tends to lower or raise the lower roll at the right hand end and by a screw 14, passing 65 through segmental slot 13^a into the journal

box 1, the bushing can be locked in position, the lower roll rotating in the bearing in said bushing. The purpose of this construction is to adjust the rolls to grasp paper which may be thicker on one side than the other, or 70 double, as in envelops, and to force it through the press uniformly. Or it can be adjusted to grasp uniformly calendered paper.

Directly under the track of antifriction 75 roller 35, I have attached to rod 69 a block 69^c, with an incline leading up thereto, so that when rod 69 moves to and fro antifriction roller 35 is raised to the top of the block. The adjustment is such that when 80 antifriction roller 35 is running on its normal track, compression spring 37 engages upper feed rolls 22 with lower feed roll 11, but when antifriction roller 35 is elevated on incline block 69^c, the feed rolls are separated. In Fig. 3, I have shown the adjusted block 69^c so that antifriction roller 35 will drop into its normal track and upper feed rolls 22 will come in contact with lower feed roll 11 as the platen is lowered for the printing. In my construction, I have formed the lower feed roll of a plurality of sections on a common shaft which correspond with and engage with the short rolls in the upper feed roll. 95

As shown in Figs. 6, 7 and 9, 10 is the lower feed plate which runs parallel to the feed rolls. It is placed over the lower feed roll, the several sections of which project upward through corresponding openings in 100 the feed plate. Lower feed plate 10 is fastened at the back end to journal boxes 1 and 2 by screws 45, from which point it extends obliquely toward the under side of the platen where it terminates in the illustrated 105 construction with a downward hook 10^a which extends the entire length of said feed plate. The purpose of this hook is to engage and support paper strippers 53 and 54 which terminate at their rear ends in corresponding upper hooks. In right hand journal box 1, I have cut a groove 1^a (shown 110 in Figs. 9 and 11) corresponding with the thickness of the lower feed plate, and at an angle corresponding to the dip given said plate. In the left hand journal box, I have inserted a stud 46 having a notch 46^a (shown in Figs. 9 and 12) cut across the projecting end thereof at an angle corresponding to the dip given the lower feed plate. Lower 115 feed plate 10 has end projections which engage the grooves 1^a and 46^a as shown in Fig. 9. Stud 46 is fastened to journal box 2 by means of a screw 48 as shown in Fig. 9. The under side of stud 46 is cut away, as 120 shown in Fig. 12, to permit rack 47 to pass under it and to support said rack 47 against lateral vibration.

In Fig. 9, 9 is the upper feed plate which 125 runs in an approximately parallel plane 130

with the lower feed plate 10. In my construction, I have formed projections at each end of the upper plate 9 which are bent downward at right angles to the plane of said plate to engage the lower feed plate and leave sufficient space between the feed plates to readily admit the paper or card board to be printed and guide the same to the upper and lower feed rolls between which it is grasped. One of these down-turned projections appears clearly in Fig. 3. 26 is a paper stop finger shaft which runs parallel to the bail shaft 15, and the ends of which are journaled in the side plates 1 and 2. I prefer to construct shaft 26 hexagonal. To said shaft, I have fitted a plurality of paper stop fingers 27 the purpose of which is to prevent paper from entering the press until the type is inked and the margins have registered. To do this, I have constructed the finger 27 in the form of a compound curve the one end of which is fastened to shaft 26 and the other end of which extends downwardly into corresponding holes in the lower feed plate 10 in front of the feed rolls. 28 is a bracket attached rigidly to shaft 26 approximately in a plane parallel with and directly over arm 34^c. In this specification, I term said bracket a pacifier. At the outside end of said pacifier 28, I have fastened the rod 31 which passes through the end of arm 34^c. 33 is a compression spring between arm 34^c and pacifier 28. 32 are lock nuts on rod 31 immediately under arm 34^c.

From this construction, it will be noted that when antifriction roller 35 is raised on inclined block 69^c, spring 33 forces pacifier 28 upward, which movement lowers the fingers 27, and when antifriction roller 35 is on its lower track, the fingers 27 are raised. 29 is an adjusting screw in the top of pacifier 28, and 30 is a lock nut attached thereto, their function being to regulate the lift in the fingers 27.

For the purpose of regulating the relative time antifriction roller 35 runs on its upper track or is held on a plane with the top of incline block 69^c, I have adjustably attached 50 to bumper block 243 a trip 244 which is in line with the right side of the track on which antifriction roller 35 runs. Bumper block 243 is attached to moving type-bed 93 as heretofore stated, and trip 244 is attached 55 to said block at such relation to the movement of rod 69 that the rear end of the trip passes under the side of antifriction roller 35, when said roller 35 is on incline block 69^c. By adjusting the trip 244 said roller 35 can drop immediately on leaving incline block 69^c, or it can be carried a distance beyond said incline block on said trip, thus delaying the movement of bail post 34. This in effect regulates the time of starting 65 the paper through the press for printing in-

asmuch as the oscillating movement of said bail post 34, communicated thereto by raising and lowering antifriction roller 35, as hereinbefore set forth, separates the upper and lower feed rolls at which time the fingers 27 are lowered to prevent the paper from being fed into the machine until the moving type-bed reaches the required point, at which time antifriction roller 35 drops into its lower track and simultaneously with 70 such movement of said roller 35, the fingers 27 rise, permitting the paper to pass through, and the upper and lower feed rolls come together forcing the paper forward under the platen. On the forward movement, the bumper block strikes the bumper strap 69^a and slides the bar 69 so that the block or lug 69^c thereon will move under and raise the roller 35. The roller will remain raised until the bumper block 80 impinges against the rear strap 69^b and thereby moves the rod 69 rearwardly, the latch 74 dropping in front of the block 73 and thereby holding the bar 69. The trip on this stroke will pass alongside the block 69^c 85 and under the roller 35 to maintain the raised position of the roller. On the forward stroke, the trip will pass from under the roller which will thereupon drop. Near the end of the stroke, the projection 243^a on 90 the bumper block will engage the inclined face 74^a on the latch and lift the latch so that the bar 69 can then move forward to carry the bumper block 69^c under the roller 35 when the bumper block strikes the strap 95 69^a.

As shown in Figs. 6, 7 and 8, 53 is the right side paper stripper and 54 is the left side paper stripper. These strippers are hooked into the lower feed plate as hereinbefore set forth, curve under the platen 3, and are fitted to slide on rods 49 and 49^a. Paper strippers 53 and 54 are adjustable lengthwise on rods 49 and 49^a by means of a clamp 60 and a clamp screw 61. The rods 105 49 and 49^a are attached to a bracket 50 on one end and a bracket 51 on the other end (the only difference in brackets 50 and 51 being that one is for the right side and the other for the left). Such brackets terminate with a horizontal portion which is fastened at one end to a forward extension of the right hand journal box, 1, and at the other end to a corresponding forward extension of the left hand journal box 2. I 110 have cut a notch 56^a in the paper strippers through which projects ejector roll 56, said roll being pivoted by a stud 59 to an arm 55 which swings on rod 49^a (shown in Fig. 8). Arm 55 is held in an upward position by a 115 spring 57. In my construction, I prefer to use a coiled tension spring 57 having one end bearing against a pin 58 on the arm 55 to push the roll against the platen. When the platen is raised, as shown in Fig. 6, 120 130

roller 56 does not touch the platen but when it is lowered into position for printing said roller 56 engages the platen under tension, thus ejecting the paper after printing at the same speed as it enters the press. The arm 55 is provided at its rear end with an extension 52 adapted to impinge against the under side of the stripper and thereby limit the downward movement of the ejector roller 56 so that said roller cannot strike the type. In Figs. 8 and 8^a, 62 is an auxiliary ejector. It is rigid and shaped like an Italic Y having the end of the forward upward projection 62^a bent at right angles to the plane 15 of the figure. The upper opening fits over rod 49 as shown in Fig. 8^a and rod 49^a fits in the curve immediately below the delta. In the tail of the Y, I have inserted one end of a straight spring 63 which is brought 20 back around a notch cut in projection 62^a and under rods 49 and 49^a when the auxiliary ejector is attached to said rods, the purpose of said spring being to hold the ejector in place on said rods under friction. 25 The upper side of said auxiliary ejector is sharpened to eliminate friction. In assembling the machine, I place the auxiliary ejector near the paper strippers. Its special value is in ejecting heavy paper or card 30 board when printed.

In Figs. 15, 16 and 17, 155 is the feeding table which I have constructed of a flat plate having twin brackets 156 on the under side at the rear end thereof. Brackets 156 have 35 inverted T-slots 156^a open at their rear ends cut therein. The ends of slots 156^a to the front and the top of slot 159^a are rounded to fit over rod 159, which rod extends at right angles to frame 138 and is carried by 40 brackets 158 at the end of the main frame. The relative position of brackets 156 and rod 159 is such that when said rod is at the forward end of the slot 156^a, table 155 can be swung thereon with rod 159 as the center, 45 and can be removed from said rod. The front end of table 155 has a downward projection with holes 45^a in each end which engage with the projections or screws 45 on the rear of journal blocks 1 and 2, when said 50 table is brought forward. The table 155 and projections 45 are in such relation that when the holes 45^a in said table engage the projection on blocks 1 and 2, rod 159 engages slot 159^a. The object of this construction is 55 to have a firm table when in use and at the same time readily removable. 157 is a stop pin in bracket 158 which engages the rear end of table 155 when it is desired to swing it backward on rod 159 without removing it. 60 See dotted lines in Fig. 17.

223 is a shelf on the right side of the machine and parallel to feed table 155. It is supported on the front end by bracket 224 on frame 138 and on the rear end by bracket 65 158 and rod 159. The function of this shelf

is to hold the paper conveniently to the means for feeding it through the press.

Having thus described my invention, what is claimed as new is:

1. In a printing machine, the combination of a frame, journal blocks at each side of the frame adapted to support an impression roller, one of said blocks being provided with a groove and the other block being provided with a lug having a notch cut therein, 70 a lower feed plate having one edge fitted in the groove in the journal block and the other edge fitted in the notch in said lug, a lower feed roll below the said plate, an upper feed roll above the feed plate, and a stop finger 75 coöoperating with the feed rolls.

2. In a printing machine, the combination of a frame, journal blocks arranged at the sides of the frame and adapted to support an impression roller, one of said journal blocks being provided with a groove and the opposite journal block being provided with a lug having a notch cut therein, and a feed plate fitting at one end in the groove in the one journal block and at its other end in the 80 notch in the said lug, said feed plate consisting of upper and lower members fitted together at both ends.

3. In a printing machine, the combination of a frame, an impression roller mounted 95 thereon, means for feeding paper to the impression roller consisting of an upper and a lower feed plate, the lower feed plate having its lower edge turned on itself to form an underlying hooked flange, and strippers 100 having upturned overlying hooked inner ends slidably engaging and supported by the flanged edge of the lower feed plate.

4. In a printing machine, the combination of a frame, an impression roller, means for feeding paper to the impression roller consisting of upper and lower feed plates, strippers adjustably attached to the lower feed plate and extending under and around the impression roller, and means for ejecting 110 the paper consisting of rollers having their peripheries extending through notches in the strippers, and means acting on said rollers to yieldably hold them to the impression roller.

5. In a printing machine, the combination of printing means, a plate for guiding paper to the printing means, strippers attached to said plate and extending past the printing means, a support for the strippers beyond 120 the printing means, means for ejecting the paper consisting of rollers carried by the strippers between said plate and said support and adapted to project above the strippers, and means carried by the strippers 125 for yieldably holding the ejector rollers projected above the strippers.

6. In a printing machine, the combination of a frame, an impression roller, means for feeding paper to the impression roller con- 130

sisting of upper and lower feed plates, strippers adjustably attached to the lower feed plate and extending under and around the impression roller, means for ejecting the paper consisting of rollers having their peripheries projecting beyond the strippers to engage the impression roller, twin parallel rods mounted transversely in the frame, ejector frames adapted to slide freely on said rods and carrying said ejector rollers, and means for locking the ejector frames to the said rods.

7. In a printing machine, the combination of a frame, an impression roller, means for feeding paper to the impression roller, strippers extending under and around the impression roller, means for ejecting the paper consisting of rollers having their peripheries disposed to engage with the impression roller, twin parallel rods, ejector frames carrying said ejector rollers and adapted to slide freely on said rods, and means for locking the ejector frames to said rods consisting of a clamp adapted to slide on one of the rods and a screw for fastening said clamp to said rod.

8. In a printing machine, the combination of a frame, an impression roller, means for feeding paper to the impression roller consisting of an upper and a lower feed plate, strippers adjustably attached to the lower feed plate and extending under and around the impression roller, means for ejecting the paper consisting of rollers having their peripheries disposed to engage the impression roller, rods secured upon the frame parallel to the impression roller and in front thereof, the strippers and ejectors being slidably mounted on said rods, means on one of said rods to secure the strippers and ejectors in a set position, and means on the other rod to yieldably hold the ejectors to the impression roller.

9. In a printing machine, the combination of a frame, an impression roller, means for feeding paper to the impression roller, strippers extending under and around the impression roller, means for ejecting the paper consisting of rollers having their peripheries disposed to engage the impression roller, and means for imparting a spring tension to said rollers consisting of rods running parallel to the impression roller, frames movable longitudinally of said rods, arms carrying said rollers and swinging freely within said frames, and coil springs within said frames adapted to hold the ejector rollers to the impression roller.

10. In a printing machine, the combination of a frame, an impression roller, means for feeding paper to the impression roller, strippers extending under and around the impression roller, means for ejecting the paper consisting of rollers having their peripheries disposed to engage the impression

roller, rods running parallel to the impression roller, ejector frames mounted on said rods, arms pivotally mounted within the ejector frames and carrying said rollers, means for yieldably holding the ejector rollers to the impression roller, and means for limiting the downward movement of the ejector rollers.

11. In a printing machine, the combination of a frame, an impression roller, means for feeding paper to the impression roller, strippers extending under and around the impression roller, means for ejecting the paper consisting of rollers having their peripheries disposed to engage the impression roller, rods running parallel to the impression roller, ejector frames mounted on said rods, arms hinged within the ejector frames and carrying said rollers, means acting on said arms for yieldably holding the ejector rollers to the impression roller, and means for limiting the downward movement of the ejector rollers consisting of an extension to said arms on the end opposite the rollers adapted to engage with the ejector frame.

12. In a printing machine, the combination of a frame, an impression roller mounted thereon, means for feeding paper to the impression roller, transversely adjustable strippers extending from said feeding means under the impression roller, a transverse support on the frame adjacent and in rear of the impression roller, ejectors slidably mounted on said support and coöperating with the strippers, and means for securing the ejectors in an adjusted position upon the said transverse support.

13. In a printing machine, the combination of a frame, an impression roller, means for feeding paper to the impression roller, strippers arranged under the impression roller, means for ejecting the paper consisting of rollers having their peripheries extending beyond the strippers and adapted to engage the impression roller, parallel rods supporting the strippers and disposed parallel to the impression roller and in front thereof, and an auxiliary ejector consisting of a member adapted to fit snugly on the parallel rods and coöperating with the impression roller and having a point projecting downwardly and adapted to lift the paper as the paper moves forward.

14. In a printing machine, the combination of a frame, an impression roller, means for feeding paper to the impression roller, strippers extending under the impression roller, means for ejecting the paper consisting of rollers extending beyond the strippers and adapted to engage the impression roller, parallel rods supporting the said strippers and ejectors and arranged parallel to the impression roller and in front thereof, an auxiliary ejector consisting of a member provided in its lower edge with notches

adapted to fit snugly over the parallel rods, and a spring extending across said notches to hold said auxiliary ejector in position on said rods.

5 15. In a printing machine, the combination of a frame, an impression roller mounted therein, means for feeding paper to the impression roller, ejector rollers coöperating with the impression roller to eject the 70 printed paper, and an auxiliary ejector coöperating with the impression roller and having a downwardly projecting point adapted to lift the paper as the same moves forward.

15 16. In a printing machine, the combination of a frame, an impression roller mounted therein, means for feeding paper to the impression roller, ejector rollers coöperating with the impression roller to eject printed 75 paper, a transverse support in the main frame for said ejector rollers, an auxiliary ejector having notches in its lower edge to engage said support, and a spring extending across said notches to hold said ejector in 80 position on said support.

20 17. In a printing machine, the combination of a frame, an impression roller, upper and lower feed rolls arranged to feed paper to the impression roller, the upper feed roll 85 intermittently engaging with the lower feed roll and consisting of a non-rotatable shaft, bushings rotatably fitted on the ends of said shaft, a tube attached to said bushings and a plurality of short rolls mounted on the 90 tube, and means for rotating said upper feed roll in the same direction as the impression roller.

40 18. In a printing machine, the combination of a frame, an impression roller mounted therein, supports projecting from the frame, a feed table, brackets projecting downwardly from the rear corners of the feed table and each having a lateral slot therein open at the rear end, closed at the 95 forward end and formed with a notch in its upper wall, a rod adapted to slide freely into such slots and notches and fastened at each end to said supports, the said table being adapted to extend obliquely down 100 from said rod to the impression roller, and means for feeding paper from the table to the impression roller.

50 19. In a printing machine, the combination of a frame, an impression roller mounted therein, supports projecting from the frame, a feed table, brackets projecting downwardly from the rear corners of the feed table and each having a lateral slot therein open at the rear end, closed at the 105 forward end and formed with a notch in its upper wall, a rod adapted to slide freely into said slots and notches and fastened at each end to the supports, the feed table being adapted to extend obliquely down from the 110 said rod to the impression roller, means for

locking the lower end of the table to the frame, and means for feeding paper from the table to the impression roller.

20 20. In a printing machine, the combination of a frame, an impression roller mounted 70 thereon, supports projecting upwardly from the frame, a feed table, brackets projecting downwardly from the rear corners of the feed table each having a lateral slot therein open at the rear end, closed at the 75 forward end and formed with a notch in its upper wall, a rod adapted to slide freely into said slots and notches and fastened at each end to said supports, a projection on the inside of one of said supports adapted 80 to engage the feed table when it is tilted backward and to limit the movement thereof, said feed table being adapted to extend obliquely downward from said rod to the impression roller, and means for feeding paper 85 from the table to the impression roller.

25 21. In a printing machine, printing means, a plate for guiding the paper toward the printing means, front stops comprising fingers, the lower ends of which are adapted 90 to project into said plate and arrest the forward edges of the paper, a shaft carrying said fingers, a bracket on said shaft, a rock arm, a compression spring between said rock arm and said bracket, and means coöperating 95 with the printing means for tilting said rock arm, a lug on the machine, and an adjustable stop on said bracket adapted to strike the lug and limit the upward stroke of the bracket. 100

30 22. In a printing machine, printing means, a plate for guiding the paper toward the printing means, front stops comprising fingers, the lower ends of which are adapted to project into said plate and arrest the forward edges of the paper, a shaft carrying 105 said fingers, a bracket on said shaft, a rock arm, a compression spring between said rock arm and said bracket, and means coöperating with the printing means for tilting said 110 rock arm, a lug on the machine, an adjusting screw passing through said lug, and a compression spring between said adjusting screw and said rock arm.

35 23. In a printing machine, printing means, a plate for guiding paper toward the printing means and having a flanged edge, guide fingers projecting past said printing means and having hooked ends slidably engaging the flanged edge of said plate permitting 115 lateral adjustment of the guide fingers, cross rods on the machine, and means adjustably securing said guide fingers to said cross rods. 120

40 24. In a printing machine, printing means, a plate for guiding paper toward the printing means, guide fingers projecting past said printing means and slidably engaging said plate, cross-rods on the machine, means adjustably securing said guide fingers to said 125 cross rods, an ejector roller carried with each 130

- guide finger and projecting above the upper surface of the guide finger, and means pivotally supporting the ejector roller permitting vertical bodily movement thereof independently of the guide finger.
25. In a printing machine, printing means, a plate for guiding the paper toward the printing means, cross rods on the machine, boxes slidable on the cross rods, guide fingers secured to the respective boxes and slidably engaging said plate, a block in each box, an ejector roller carried by each block and spring means for holding each block against the upper wall of the associated box.
- 10 26. In a printing machine, printing means, a plate for guiding the paper toward the printing means, cross rods on the machine, boxes slidable on the cross rods, guide fingers secured to the respective boxes and slidably engaging said plate, a block in each box, an ejector roller carried by each block, and spring means for holding each block against the upper wall of the associated box.
- 15 26. In a printing machine, printing means,

a plate for guiding the paper toward the printing means, cross rods on the machine, boxes slidable on the cross rods, guide fingers secured to the respective boxes and slidably engaging said plate, a block in each box, an 20 ejector roller carried by each block and spring means for holding each block against the upper wall of the associated box, and a thumb screw in each box bearing against one of said cross rods.
